UNITED STATES PATENT OFFICE.

JAMES L. G. WEBB, OF GOODELLS, MICHIGAN.

LANTERN.

1,182,824.

Specification of Letters Patent.

Patented May 9, 1916.

Application filed January 17, 1916. Serial No. 72,516.

To all whom it may concern:

Be it known that I, JAMES L. G. WEBB, a citizen of the United States, residing at Goodells, in the county of St. Clair and State of Michigan, have invented new and useful Improvements in Lanterns, of which the following is a specification.

This invention relates to lanterns and it consists in the novel features hereinafter described and claimed.

An object of the invention is to provide a lantern with reflectors so positioned with relation to the light as to cast the rays of maximum intensity beyond the globe of the lantern in order that maximum illumination may be had.

With the above object in view the lantern includes a frame having a font located at the lower portion thereof and serving as a base for the frame. A wick holder is detachably mounted in the font and a globe holder is movably mounted upon the frame and is adapted to support a globe over the wick holder. A circular wick is employed in the wick holder and if desired the wick may be made in sections, there being provided means for moving each section of the wick independently of the other section. A reflector is supported in the wick holder and is positioned centrally with relation to the wick. A reflector is supported from the upper part of the frame of the latter and extends down toward the first mentioned reflector.

In the accompanying drawings:—Figure 1 is a side elevation of the lantern. Fig. 2 is a detail sectional view of the upper portion of the same. Fig. 3 is a horizontal sectional view of a portion of the same cut on the line 3—3 of Fig. 4. Fig. 4 is a detail sectional view of the lower portion of the same.

The lantern comprises a frame 1 which may be of any form or pattern. A font 2 is carried at the lower portion of the frame 1 and may serve as a supporting base for the same. The font is provided at its top with a nipple 3 which is normally closed by a plug 4 and through which, when the plug is removed, oil may be poured into the font. A bail handle 5 is pivotally connected with the upper portion of the frame 1 in the usual manner. The font 2 is provided at its top side with an annular collar 6.

A wick holder is slidably inserted in the collar 6 and comprises outer and inner annular wick guides 7 and 8. These guides

are spaced from each other and at their lower ends they are split vertically as at 9. The outer wick guide 7 is adapted to fit snugly against the inner surface of the collar 6 and by reason of the fact that the said guide is split, it will have close contact with the inner surface of the collar 6, and inasmuch as the lower portion of the inner guide 8 is also split it will remain at a proper spaced distance from the outer wick guide 7. The outer wick guide 8 is provided at its upper end with an outstanding flange 10 having openings 11 whereby air may pass into the globe which is supported above the wick holder as hereinafter explained. Wick sections 12 fit in the wick holder between the inner and outer guides 8 and 7 and the said sections at their upper ends abut against each other thereby forming a circular wick. Shafts 13 are journaled in the upper portion of the wick holder and are provided with toothed wheels 14 which engage the wick sections 12 and serve as means for raising and lowering the said sections when the shafts 13 are turned.

A cone shaped reflector 15 preferably of burnished sheet metal is screwthreaded in the innermost wick guide 8 just below the upper end thereof and the said reflector is provided at its upper central portion with one or more openings 16 which afford ventilation for the interior of the font 2 and prevent the said font from being exposed to gas pressure in view of the fact that should gas generate in the tank it may escape therefrom through the opening 16.

A ring 17 is supported above the wick holder and is provided at one side with a hook 18 which engages in a loop 19 provided at one side of the frame 1, and the said ring is provided at its opposite side with a resilient catch 20 adapted to engage in notches 21 provided in a guide 22 located at the side of the frame 1. Resilient frames 23 are mounted upon the ring 17 and bear against the opposite sides of a globe 24 when the base of the globe rests upon the ring 17. Thus means is provided for holding the globe in position upon the ring 17.

A cylinder 25 is carried at the upper end of the frame 1 and is provided at its lower end with an outstanding flange 26. The said cylinder 25 is provided at its upper end with an inwardly disposed flange 27. A sleeve 28 is slidably mounted in the cylinder

25 and is provided at its lower end with an outstanding flange 29 which bears against the upper edge of the globe 24. The sleeve 28 is provided above its lower edge with another outstanding flange 30 which at times is adapted to engage the flange 26 of the cylinder 25 whereby the upward movement of the sleeve 28 in the said cylinder is limited. The sleeve 28 is provided below the flange 30 with a series of openings 31. A coil spring 32 surrounds the upper portion of the sleeve 28 and is interposed between the flange 27 of the cylinder 25 and the upper surface of the flange 30 of the sleeve 28. The spring 32 is under tension with a tendency to hold the lower end of the sleeve 28 in engagement with the upper edge of the globe 24.

A cylinder 33 is screwthreaded in the upper end of the sleeve 28 and is provided at its upper end with cap 34. The cylinder 33 is provided at its sides and below the cap 34 with a series of openings 35. A stem 36 passes longitudinally through the sleeve 28 and a threaded shank 37 of the said stem passes centrally through the cap 34. The shank 37 is provided at its upper end with a knob or handle 38. A tap 39 is positioned upon the upper side of the cap 34 and the shank 37 is threaded through the said cap. At its lower end the stem 36 carries a substantially globular reflector 40 which is located in the intermediate portion of the globe 24 and above and spaced from the reflector 15. By turning the stem 36 by using the knob or handle 38 the shank 37 moves through the tap 39 and consequently the reflector 40 may be adjusted in its position with relation to the reflector 15.

When it is desired to apply a match to the upper ends of the wick sections for the purpose of lighting the lantern the operator grasps the spring catch 20 and moves the same from the lowermost notch 21 in the guide 22 to the uppermost notch in the said guide. This lifts the ring 17 and elevates the globe 24; consequently a match may be inserted below the ring 17 and the wick may be lighted. After the wicks are lighted the catch 20 is disengaged from the uppermost notch 21 of the guide 22, and the globe 24 will be turned under the tension of the spring 32. During the upward movement of the globe the sleeve 28 is moved in an upward direction but the upward movement of the said sleeve is limited with relation to the cylinder 25 by means of the flange 30 which is carried by the sleeve. The said flange 30 comes in contact with the lower side of the flange 26 and hence the upward movement of the said sleeve is limited. By using the shafts 13 one or the other of the wick sections may be raised or lowered and hence if it is desired to have a flame of uniform intensity or brightness all around the wick

holder, the wick may be adjusted with relation to each other to cause the production of such a flame or light. By providing the wick in sections the disadvantage incident to a continuous wick is avoided in view of the fact that in a continuous wick it sometimes burns brighter at one side than at the other, and therefore, in order to have a uniform and steady flame, it is necessary to trim the wick. By arranging the wicks as shown and described the necessity of trimming the same in order to produce a uniform flame or light is avoided.

When the lamp is hung upon an elevated support the rays are deflected in a downward direction by the reflector 40 and when the lantern is lowered into a pit or other depressions the rays of light are cast in an upward direction by the reflector 15. In view of the fact that both of the said reflectors are at the center of the flame or light they cast out rays of light around all parts of the globe and consequently a bright or intense light is had.

From the foregoing description taken in conjunction with the accompanying drawings it will be seen that a lantern of simple and durable structure is provided and that the parts mutually coöperate with each other to give a very brilliant or bright light, and the parts may be manipulated to cause the flame all around the wick of a uniform brightness or volume.

Having described the invention what is claimed is:—

1. A lantern comprising a frame, a font connected to the frame, a collar provided upon the font, a wick holder including outer and inner guides spaced from each other, said guides being provided at their lower portions with splits, the wick holder fitting snugly in the collar, wick sections located in the wick holder between the guides and means for moving each wick section independently of the other wick section.

2. A lantern comprising a frame, a font carried by the frame, a wick holder mounted upon the font, a wick carried by the wick holder, a reflector carried by the wick holder, a globe supported above the wick holder, and a reflector supported in the upper portion of the globe and centrally positioned with the relation to the wick.

3. A lantern comprising a frame, a font carried by the frame, a collar mounted upon the font, a wick holder detachably mounted in the collar, a reflector carried by the wick holder, a wick carried by the wick holder and surrounding the said reflector, a globe supported above the wick holder and a reflector supported above the first mentioned reflector, and means for adjusting the position of the second mentioned reflector with relation to the first mentioned reflector.

4. A lantern comprising a frame, a font carried by the frame, a wick holder mounted upon the font, a circular wick carried by the wick holder, a reflector carried by the wick holder, a wick carried by the wick holder and surrounding said reflector, a globe supported above the wick holder, resilient means for holding the globe in position above the said wick holder, a stem adjustably supported above the wick holder,
- 5
- 10

and a reflector carried by the stem and spaced from the first mentioned reflector and located centrally with relation to the wick.

In testimony whereof I affix my signature in presence two witnesses.

JAMES L. G. WEBB.
